UNITED STATES PATENT OFFICE.

GEORGE H. DAY, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

EYE-PROTECTOR.

1,298,908.

Specification of Letters Patent.

Patented Apr. 1, 1919.

Application filed September 6, 1916. Serial No. 118,749.

To all whom it may concern:

Be it known that I, GEORGE H. DAY, a citizen of the United States, residing at Southbridge, in the county of Worcester and State 5 of Massachusetts, have invented certain new and useful Improvements in Eye-Protectors, of which the following is a specification.

This invention relates to improvements in eye protectors and has particular reference 10 to that form of protector in which a leather or like flexible mask is employed for retaining or protecting lenses in position before the eyes.

One of the leading objects of the present 15 invention is the provision of an improved construction which will permit of a certain amount of lateral vision through what is normally the closed sides of the protector.

A further object of the invention is the 20 provision of a novel and improved construction of side to facilitate the ready insertion or removal of the auxiliary lateral closures without the necessity of special frames or the like, such as have previously been employed.

A further object of the invention is the 25 provision of improved means for readily and satisfactorily ventilating a close fitting mask or goggle.

Other objects and advantages of my improved construction should be readily apparent by reference to the following description taken in connection with the accompanying drawings, and it will be understood 30 that I may make any modifications in the specific details of construction shown and described within the scope of the appended claims without departing from or exceeding the spirit of my invention.

Figure I represents a front view of a protector constructed in accordance with and embodying my invention.

Fig. II represents a side elevation thereof.

Fig. III represents a sectional view as on 45 the line III—III of Fig. I.

Fig. IV represents a sectional view taken on the line IV—IV of Fig. II.

Fig. V represents a plan view of the screen member removed.

Fig. VI represents a side elevation illustrating a transparent member inserted in place of the screen member.

Fig. VII represents a slightly different construction of retaining device.

In the drawings, in which similar charac-

ters of reference are employed to denote corresponding parts throughout the several views, the numeral 1 designates a leather or other flexible mask having secured thereto as by the staple clips 2, the head band portions 3 for retaining the device in position on the face. Suitable metallic or like rims 4 secured around the edges of the central visual apertures in the mask serve to securely retain in position the eye protecting 65 lenses 5, the material of the mask being preferably connected to the rims as by the tubular rivets 6.

In that form of my invention illustrated in Figs. I to IV inclusive, I have shown the 70 mask as formed with the overlapping side portions 6' and 7, it being understood that the entire mask if desired may be formed from a single flat piece of material, it being necessary to split the same at suitable points 75 and bring the material together to produce a cup like formation. Hitherto, however, it has been customary to simply form an ordinary seam or joint at the points where the parts are brought together.

In the carrying out of my invention, however, in place of forming a regular seam, as previously referred to, I form the parts with a pronounced overlap, as will be understood by reference to Fig. III, from which it will 85 be seen that the parts are united by seams, as at the points 8, providing therebetween the central pocket 9 closed at the outer end both by circumferential stitching, and by the head band retaining clip 2, but open at 90 its inner end adjacent the lens 5, which thus serves as a closure for the open end of the pocket.

The parts being thus formed I preferably 95 cut away the greater portion of the overlapped material to provide the apertures or windows 10 surrounded by a slight frame portion.

The device having been thus constructed, and preferably prior to the securing of the 100 lenses 5 within their rims 4, I slide from the open or lens side of the pocket 9 my transparent or ventilating members, which preferably comprise the screens 11 having a reduced neck 12 at one end adapted to project between the two arms of the head band securing clip 2 to insure a proper fit of the screen member within the pocket, securely 105 limiting its outward movement and steadily limiting its inward or withdrawing move- 110

ment being prevented by engagement between the inner end of the screen member 11 and the lens 5.

It will thus be seen that this screen member provides thorough and satisfactory ventilation at both sides of the goggle, while at the same time being transparent permits of a limited amount of vision or notice of objects approaching on either side, affording thus ventilation, and protection at both sides of the goggle or eye protector.

If preferred, however, in place of employing the screening material, I may employ a suitable transparent material, such as mica, celluloid or glass. In any event the auxiliary transparent member is placed in the pocket in substantially the same manner and is retained in position by the presence of the lens 5.

20 In Fig. VII, I have illustrated a slight modification of my invention, in which in place of the overlap providing the pocket to receive the transparent member, an auxiliary framing device 13 is secured as by stitching at the sides 14 and end 15 to the shield or mask 1, but the pocket as previously described being left open at the lens side.

I claim:

1. In a protector, the combination with a flexible mask or shield member, having an aperture formed therein, of means surrounding the aperture to provide a receiving groove or pocket open at one end, a flexible transparent member arranged within said aperture and having its edges disposed within said groove or pocket and lens retaining means at the open end of the pocket whereby the transparent member will be locked in position by the presence of a lens in the lens retaining means.

2. In a protector, the combination with a lens securing rim, of a mask portion carried by the rim and having a pronounced overlap, the overlapped portions being connected to each other adjacent their edges only, whereby a central pocket is provided intermediate said edges, means for closing the outer end of the pocket, the overlapped portions being cut away to provide a central aperture for the pocket, and a transparent protecting member inserted within the pocket to form a closure for the aperture, said member being retained by the engage-

ment between its circumferential edge portions and the remaining overlaps.

55

3. In a device of the class described, including a mask portion having visual apertures therein, visual protecting members removably disposed within said apertures, flexible side shields formed integral with the mask having apertures formed therein and flexible transparent protecting members removably disposed within said apertures, as and for the purpose set forth.

4. The combination with a pair of mask sections each having an aperture near the edge thereof, of means securing the parts in over-lapped relation, with a free portion surrounding the apertures, means for closing one end of the apertured pocket thus provided, and lens retaining means secured to the overlapped members adjacent the other end of the pocket whereby a device inserted through the open end of the pocket will be locked in position by the presence of a lens in the lens securing means.

70

5. In a protector, the combination with a lens rim, of a flexible shield portion extending rearwardly from the rim, said shield portion having an aperture formed therethrough and a frame pocket encircling the aperture and opening upon the lens, whereby the lens serves as a closure for the mouth of the pocket, and a transparent member inserted in the pocket through the open mouth and locked in position by the fit of the lens against the mouth of the pocket.

80

6. An eye protector, including flexible side shields having apertures formed therein and flexible transparent protecting members within the apertures, as and for the purpose set forth.

90

7. An eye protector, including flexible side shields having apertures formed therein and fabric windows within the apertures, as and for the purpose set forth.

95

8. An eye protector, including flexible side shields having apertures formed therein, and wire mesh windows secured within the apertures, as and for the purpose set forth.

100

In testimony whereof I affix my signature in the presence of two witnesses.

GEORGE H. DAY.
